United States Patent

Des. 238,405

Patented Jan. 13, 1976

238,405

NECKTIE RACK

Bert Harold Athey, 170 N. Thurston Ave.,
Los Angeles, Calif. 90049

Filed Mar. 11, 1974, Ser. No. 449,940

Term of patent 14 years

Int. Cl. D6—04

U.S. Cl. D6—28

FIG. 1 is a perspective view of my necktie rack; and FIG. 2 is a side elevational view of the necktie rack design.

I claim:

The ornamental design for a necktie rack, as shown.
